DOOR BUMPER

Sidney C. Groeschel, Columbia, S. C., and Aaron G. Dawson, Oteen, N. C.

Application June 22, 1937, Serial No. 149,736

8 Claims. (Cl. 16—86)

Our invention relates generally to means for cushioning the slamming of a door, and particularly to means of this character which is mounted on the door and occupies a position between that part of the door which ordinarily strikes the jamb in closing, and the jamb itself, in the form of a compressible or shock absorbing pad, and an important object of our invention is to provide simple and effective means of this character which can be constructed in various inexpensive forms.

Another important object of our invention is to provide bumper means of the character indicated which is adapted to be mounted on one of the door handles and frictionally engaged therewith in a manner to rotate with the door handle so as to be positioned by the door handle normally in the shock absorbing position.

Another important object of our invention is to provide bumper means of the character indicated above which has a carrying portion securely fastened to the door handle by means of structure already present on the conventional door handle, and whereby the bumper means is positively positioned by reason of the position of the door handle.

Other important objects of our invention will be apparent from a reading of the following description taken in connection with the drawings, wherein for purposes of illustration we have shown preferred embodiments of our invention.

In the drawings:—

Figure 1 is a general elevational view of the inner side of a door showing an embodiment of the invention mounted on the door handle thereof.

Figure 2 is an enlarged top plan view and horizontal section showing the relationship of the door, the bumper and the door jamb, and the manner in which the bumper is mounted on the door handle.

Figure 3 is an end or edge elevational view of Figure 1.

Figure 4 is a side elevational view of the bumper per se.

Figure 5 is an end elevational view of Figure 4.

Figure 6 is a view similar to Figure 2 but showing a modified form of bumper.

Figure 7 is a longitudinal vertical sectional view taken through Figure 6 approximately on the line 7—7 and looking upwardly in the direction of the arrows.

Referring in detail to the drawings, and with particular reference to the embodiment of the invention shown in Figures 1 through 4, the numeral 1 generally designates the bumper which in

this instance is made of suitable compressible and resilient material, such as rubber and comprises an elongated shank on one end of which is an integrally formed eye 2 which has the opening 6 which frictionally receives the shank portion 3 of the door handle 4 closely adjacent to the inner surface of the door 5. The remaining end of the shank of the bumper has a cross head 7 integrally formed thereon which is adapted to assume, normally, a position between the inner side of the free edge of the door 5 and the opposed face of the door jamb 8 on the door frame 9 as particularly well illustrated in Figure 2 of the drawings. The opening 6 in the eye of the bumper is small enough to produce a strong frictional fit on the shank of the door handle, so that it will be substantially securely mounted thereon and will turn with the door handle when the door is turned. The bumper is so positioned on the shank of the door handle that when the door handle is in the normal unoperated position the head 7 will lie in the position shown in full lines in Figure 1 and Figure 2 of the drawings, so that should the door be slammed from an open position, the head 7 of the bumper will absorb the shock and prevent injury to the door and the door jamb as well as reduce the noise ordinarily occurring in the slamming of a door.

Referring now to the embodiment of the invention shown in Figures 6 and 7, the numeral 10 generally designates the embodiment which in this instance comprises a flat metal spring arm 11 which is inserted in and fastened at one end in a resilient compressible material head 1a and has its opposite end bent into a coil 12 and of a diameter permitting the telescoping of the shank portion 3a of the door handle 4a thereinto. The free end of the coil 12 is provided with an opening 13 to receive the set screw 14 which is normally existent on the door handle for engaging the squared shank 15 of the door handle axle whereby the door handle is secured in place on the axle. The screw 14 is passed through the opening 13 and threaded into the shank 3a, so that the member 11 extends exactly in the position required to place the cross head 1a in the shock absorbing position relative to the jamb 8a of the door frame 9a and the inner face of the door 5a as illustrated in Figures 6 and 7, while the door handle 4a is in its normal or initial position. When the door handle 4a is rotated in locking the door to close the same, the bumper will be carried by the motion of the door handle to an inoperative position such as those indicated in dotted lines in Figure 1 of the drawings.

Although we have shown and described herein preferred embodiments of our invention, it is to be definitely understood that we do not desire to limit the application of the invention thereto, and any change or changes may be made in the materials and in the structure and arrangement of the parts, within the spirit of the invention and the scope of the subjoined claims.

What is claimed as new is:—

10. 1. In combination with a door in a door frame, said door having a rotatable handle and the frame having a jamb against which the free edge of the door is normally engageable in coming to a closed position, a bumper member mounted on the door handle and movable therewith and having a resilient part for fitting between the door jamb and a part of the door for cushioning the closing of the door.
15. 2. In combination with a door in a door frame, said door having a rotatable knob and the frame having a jamb against which the free edge of the door is normally engageable in coming to a closed position, a resilient member mounted on the door handle and normally positioned between the door jamb and the said free edge of the door for cushioning the closing of the door, and means positively securing the resilient member to said door knob for rotation therewith.
20. 3. In combination with a door in a door frame, said door having a rotatable knob and the frame having a jamb against which the free edge of the door is normally engageable in coming to a closed position, a resilient member mounted on the door handle and normally positioned between the door jamb and the said free edge of the door for cushioning the closing of the door, said resilient member having a resilient and compressible cross head at its free end which is directly engageable by the free edge of the door and the face of the door jamb.
25. 4. In combination with a door in a door frame, said door having a rotatable knob and the frame having a jamb against which the free edge of the door is normally engageable in coming to a closed position, a resilient member mounted on the door handle and normally positioned between the door jamb and the said free edge of the door for cushioning the closing of the door, said resilient member having a resilient and compressible cross head at its free end which is directly engageable by the free edge of the door and the face of the door jamb, said resilient member comprising a resilient shank on which said head is fastened.
30. 5. In combination with a door in a door frame, said door having a rotatable knob and the frame having a jamb against which the free edge of

the door is normally engageable in coming to a closed position, a resilient member mounted on the door handle and normally positioned between the door jamb and the said free edge of the door for cushioning the closing of the door, said resilient member having a resilient and compressible cross head at its free end which is directly engageable by the free edge of the door and the face of the door jamb, said resilient member including an element encircling a portion of the door knob.

5. 6. In combination with a door in a door frame, said door having a rotatable knob and the frame having a jamb against which the free edge of the door is normally engageable in coming to a closed position, a resilient member mounted on the door handle and normally positioned between the door jamb and the said free edge of the door for cushioning the closing of the door, said resilient member having a resilient and compressible cross head at its free end which is directly engageable by the free edge of the door and the face of the door jamb, said resilient member including an element encircling a portion of the door knob, said door knob having thereon a set screw, and said element having an opening receiving said set screw whereby said set screw positively fastens said element in place on the door handle.

30. 7. In combination with a door in a door frame, said door having a rotatable knob and the frame having a jamb against which the free edge of the door is normally engageable in coming to a closed position, a resilient member mounted on the door handle and normally positioned between the door jamb and the said free edge of the door for cushioning the closing of the door, said resilient member having a resilient and compressible cross head at its free end which is directly engageable by the free edge of the door and the face of the door jamb, said compressible member being integrally composed of a single piece of resilient compressible material.

35. 8. In combination with a door in a door frame, said door having a rotatable knob and the frame having a jamb against which the free edge of the door is normally engageable in coming to a closed position, a resilient member mounted on the door handle and normally positioned between the door jamb and the said free edge of the door for cushioning the closing of the door, said resilient member being composed of a flexible metallic shank, and said head being formed of compressible material and secured to the free end of the shank.

40. SIDNEY C. GROESCHEL.
45. AARON G. DAWSON.
